UNITED STATES PATENT OFFICE.

VICTOR LIST AND JAKOW KOSAKOFF, OF MOSCOW, RUSSIA.

PETROLEUM OR OIL ENGINE.

SPECIFICATION forming part of Letters Patent No. 550,185, dated November 19, 1895.

Original application filed August 3, 1893, Serial No. 482,152. Divided and this application filed June 27, 1894. Serial No. 515,863. (No model.) Patented in France April 21, 1893, No. 229,527; in Belgium May 20, 1893, No. 104,740; in Italy May 20, 1893, LXVII, 30; in Switzerland May 27, 1893, No. 7,061; in Norway June 9, 1893, No. 3,296, and in England June 23, 1893, No. 12,388.

To all whom it may concern:

Be it known that we, VICTOR LIST and JAKOW KOSAKOFF, subjects of the Emperor of Russia, residing at Moscow, in the Russian Empire, have invented new and useful Improvements in Petroleum or Oil Engines, (for which we have obtained patents in Belgium, No. 104,740, bearing date May 20, 1893; in Great Britain, No. 12,388, bearing date June 23, 1893; in France, No. 229,527, bearing date April 21, 1893; in Italy, vol. LXVII, No. 30, bearing date May 20, 1893; in Switzerland, No. 7,061, bearing date May 27, 1893, and in Norway, No. 3,296, bearing date June 9, 1893,) of which the following is a specification.

This application is a division of an application filed by us August 3, 1893, Serial No. 482,152.

Our invention relates to two-cycle engines worked by gas or vapor generated from mineral oil or liquid hydrocarbon, hereinafter referred to as "oil;" and it consists of certain novel features and combinations of parts, which will be separately pointed out in the claims concluding this specification.

The chief object of our invention is to effect improvements in the action as regards the development of motive power, and also a simplification in the valve-gear, so that the motor is rendered very accurate and effective in its operation. Moreover, to prevent any waste in the form of unconsumed gases of the oil by not forming the explosive mixture before the residual products of explosion are expelled and the exhaust closed, and at the same time to reduce the number of valves commonly employed for the admission and discharge of the gas and air and products of combustion. In the two-cylinder engine hereinafter described this result is obtained with great perfection by dispensing with any air-inlet valves commonly used and valves in the explosion-chamber; the air-supply being effected by suitably-combined action of the two working pistons in such a manner that one cylinder supplies the other with the air and charging mixture, the explosion taking place simultaneously and with equal effect in both cylinders, one air supply and

compressing chamber being common to the two cylinders.

Referring now to the accompanying sheet of drawings, Figure 1 illustrates in transverse section, Fig. 2 in longitudinal section, and Fig. 3 in end elevation, a two-cylinder engine constructed according to this invention.

As shown in the drawings, the two pistons B' and B², which work in two cylinders A' and A², represented for convenience of illustration as being arranged at an angle to one another, are connected to one crank-shaft d by two connecting-rods b' and b² in such a manner that they simultaneously transmit motion to the said shaft. The connecting-rods and crank work in a casing c*, inclosing a space or chamber D, communicating as follows, viz: first, with the upper ends of the cylinders A' and A² directly; second, with the explosion chamber C' C² C³, through a pipe F, annular passage f⁰, and orifices f' in the periphery of the cylinder A'; third, with the external atmosphere through a passage e⁰, which is opened when the two pistons B' B² require to draw air into the chamber D' by means of a balanced piston-valve E'. A flat side-valve may be employed in place of this piston-valve if preferred.

During the rotation of the shaft in the direction of the arrow, and owing to the arrangement of the connecting-rods, Fig. 1, and the inclined position of the two cylinders relatively to one another, the piston B² has a certain amount of lead relatively to the piston B', as indicated in Fig. 1, equal to about the height of the exhaust-openings or circumferential orifices f² in the cylinder A². Consequently when the piston B² is at the upper extremity of its stroke the piston B² has already commenced the descent and has just covered the orifices f². The same effect—namely, a lead of one piston relatively to the other—may likewise be obtained when the cylinders are arranged parallel to one another by connecting the pistons to separate cranks, so adjusted that one piston moves in advance of the other to the required extent. When the piston B² descends, followed after a short interval by the piston B', both

pistons draw air through the now open passage e^0 from the atmosphere into the chamber D. After the orifices f^2 and f' are successively closed the air is compressed in the chambers or spaces C' C² of the cylinders A' A², as well as in the explosion-chamber C³, connecting the said cylinders. During this compression period the pump G forces oil through the vaporizer H, whence it passes, heated and partly in the form of vapor and partly as fine spray, through the open valve I of the vaporizer, into the explosion-chamber C³, where it is caused to impinge against the deflecting-plate J in order to obtain a thorough mixture with the air. After the compression of the explosive mixture formed in the chamber C³ in the first place, the piston B', having reached the lower end of its stroke, and the piston B², owing to its lead, having previously commenced its ascent, the ignition is effected by means of the igniter-tube o and both pistons are forced upward by the explosion. During the whole of this upward movement the products of the explosion expand in the cylindrical chambers or spaces C' C², as well as in the explosion-chamber C³, until the piston B² uncovers the orifices f^2 and the pressure in the chambers C' C² C³ falls to one atmosphere, owing to the escape of the products of the explosion through these orifices into an exhaust-pipe g. During this upward movement of the pistons the air-passage e^0 is closed by the slide or piston valve E', so that air is moderately compressed in the chamber D and in the pipe F.

Immediately after the pressure under the cylinders commences to fall to one atmosphere, owing to the opening of the orifices f^2 , the piston B' commences to uncover the orifices f' , so as to admit air from the chamber D, through the pipe F, into the chamber or space C'. This air assists in driving out the products of combustion remaining in the chambers C' C² C³, through the orifices f^2 , into the exhaust-pipe g.

During the descent of the pistons the orifices f^2 are first closed, and immediately thereafter the orifices f' are likewise closed and the air, partly mixed with products of combustion in the chambers C' C² C³, is compressed, being at the same time mixed with the oil-vapor and spray introduced into the chamber C³. After the piston B' has arrived at the lower end of its stroke the explosive mixture is ignited and the operations are repeated as before.

The valve-gear for opening and closing the air-passage e^0 and for working the oil-pump G and vaporizer-valve I receives motion from a rod h, actuated by an eccentric g, fixed upon the crank-shaft d. The slide or piston valve E' is connected by a bolt l to a block i', provided with a projection n and sliding in a slotted head h⁴ on the eccentric connecting-rod h. A bent or bell-crank catch-lever s³ s⁴ is pivoted at r in a recess h³ in the said rod. A spring y acts upon the arm s⁴ and tends to

press it against the side of the eccentric-rod h and cause it to engage with the aforesaid projection n in such a manner that the movements of the eccentric are transmitted to the piston-valve E'. This valve descends with the eccentric-rod h and on the ascent of the latter is raised when the lower edge m' m² of the slot in the connecting-rod has ascended 75 sufficiently to enable it to act upon the block i'. The eccentric is fixed upon the shaft d at such an angle relatively to the crank as to cause the passage e^0 to be open during the descent of the two pistons B' and B². 80

During the descent a projection E², cast on the piston-valve E', acts upon a sliding rod t', connected to the extremity of a lever x oscillating on a fixed pivot Q'. This lever is joined at M³ to a link t², which transmits motion to 85 the plunger G' of the oil-pump G. The extremity n' of this lever is connected to the valve-rod m of the vaporizer-valve I. By these means the oil which is drawn into the pump G by the plunger G', acted on by a spring L², is forced through the vaporizer and through the orifice controlled by the valve I into the explosion-chamber C³. The upper extremity of the rod t' is provided with a plate p³, which is acted on by the slide E' on the 90 descent of the latter. The lower end of the said rod t' is provided with a screw-thread, by which it is connected to a head S, connected by a pin T to the extremity of the lever x. By rotating the rod t' it can be screwed in or 100 out of the head S so as to adjust the length of the said rod and thereby regulate the stroke of the oil-pump piston or plunger G', and the amount of oil introduced into the explosion-chamber. This adjustment is obtained by 105 simply rotating a milled disk U by hand. A spring V, engaging with recesses or notches in the said disk, serves to retain the rod t' in the position in which it is adjusted relatively to the head S. 110

In order to obtain a regular and uniform working of the engine under varying loads an ordinary centrifugal governor is employed, which is attached to the crank-shaft d. This governor is provided with balls R, Fig. 2, 115 which fly out when the engine runs at an excessive speed and act through levers u² and u³ upon an annular surface, such as a disk L³, placed upon a boss or sleeve v² capable of sliding upon the shaft, and in the case of an 120 excessive speed assuming the position indicated by dotted lines in Fig. 2. The arm s³ of the catch-lever s³ s⁴, carried by the connecting-rod for the purpose of enabling the latter to act upon the piston-valve E', then 125 comes in contact during the ascent of the connecting-rod with the edge of the disk L³. This has the effect of moving the extremity s⁴ away from the projection n and preventing it from lowering the valve E' during the next 130 downward movement of the connecting-rod h, which simply slides along the head of the block i' without moving the valve. Consequently the passage e^0 remains closed and the pistons

B' B² are prevented from drawing in a fresh charge of air. The movement of the oil-pump plunger being at the same time suspended, no explosive mixture is formed and 5 no explosion takes place until, owing to a reduction of the speed, the disk L³ is enabled to return to its original position (represented by full lines in the drawings) and allows the spring y to act upon the arm s⁴ and draw 10 it back into the proper position for acting, through the projection n, upon the valve E', thereby enabling air to be drawn into the air-chamber and oil to be injected into the combustion-chamber, so that the explosions take 15 place as before.

We are aware that prior to our invention two-cylinder engines have been constructed, the rods of both pistons being connected to the same crank, so that they perform their 20 strokes together, both acting as pumps for compressing a charge of air or of gaseous mixture in a closed space containing the crank. We therefore do not claim such a combination, broadly; but 25 What we do claim as our invention, and desire to secure by Letters Patent, is—

1. The combination, in a two-cycle oil or petroleum motor, of two cylinders, having circumferential orifices with pistons controlling the latter and arranged so, that one of the pistons has a lead relatively to the other equal to about the height of the circumferential orifices, a common explosion chamber C' C² C³, common air supplying and compressing chamber D, communicating by a space or chamber F with one of the cylinders A' through said orifices (f'), while the orifices (f²) of the other cylinder A² open into the exhaust pipe g, substantially as and for the purpose specified. 30 2. In a valve gear for oil or petroleum engines the combination of a single eccentric (g) driving an eccentric rod (h), with a catch lever s³ s⁴ pivoted at r, block i' on the bolt l 35

of the air slide or valve E', and means whereby the motion of this latter is transferred to 45 the moving parts of the oil-pump G and the vaporizer valve I, substantially as described with reference to Figs. 2 and 3.

3. In a valve gear for oil or petroleum engines the combination of an eccentric g, eccentric rod h, catch lever s³ s⁴, block i' on bolt l of the air valve E' with a projection E² of the latter, opposite to a rod t' combined with a lever x, connected to the reciprocating rod t² of the plunger G' of the oil pump and to 50 the rod m of the vaporizer valve I, and means for controlling the air valve, oil pump and vaporizer valve by the governor, substantially as described.

4. In a valve gear for oil or petroleum motors the combination of a single eccentric g, rod h, catch lever s³ s⁴, block i' on bolt l of the air valve E', projection E² therefrom, rod t', lever x, rod t² of the oil pump plunger and rod m of the vaporizer valve I, with a circular surface or plate L³ of the governor boss or sleeve v², the end s³ of the catch lever being opposite to the said circular surface or plate in case the machine runs at too high a speed, substantially as set forth. 60

5. The lever x, having head S, pivoted at T and the rod t' being rotatable by disk U screwed into said head, substantially as shown in Fig. 2 and for the purpose specified. 70

In testimony whereof we have hereunto set 75 our hands in the presence of two subscribing witnesses.
